UNITED STATES PATENT OFFICE

ALEXANDER NYMAN, OF EAST ORANGE, NEW JERSEY, ASSIGNOR TO DUBILIER
CONDENSER CORPORATION, A CORPORATION OF DELAWARE

ELECTRICAL CONDENSER

Application filed May 24, 1924. Serial No. 715,629.

This invention relates to improvements in electrical condensers; particularly condensers for use in signalling apparatus.

An object of the invention is to provide an electrical condenser which is designed to give high efficiency and small losses and which is particularly adapted for high power radio circuits operating with short wave lengths.

10 Further objects and advantages of the invention will appear from the following description, and the novel features of my improvements will be defined in the appended claims. But the disclosure is illustrative only and I may make changes in structural details to the full extent indicated by the general meanings of the terms in which the claims are expressed.

On the drawings,

20 Figure 1 is a front view of a condenser according to my invention;

Figure 2 is a section on the line 2—2 of Figure 1;

25 Figure 3 is a side view of a central tubular member which forms one of the terminals of the condenser;

Figure 4 is a section through one of the wedge blocks for exerting pressure upon the parts of the condenser;

30 Figure 5 is a side view of a portion of one of the tightening elements or rods for the condenser; and

Figure 6 is a vertical, sectional view of a modification.

35 The same numerals identify the same parts throughout, on the drawings.

The condenser presented in Figure 1 consists of a number of sections, each section made up of sheets of some suitable insulation or dielectric such as mica, interleaved with sheets of conductive material, such as thin metal foil. These sections 1 are arranged in pairs, and between each pair of adjacent sections is a wedge block 4, having a hole 5 through it. The various pairs of sections with the wedge blocks between them are in sufficient number to make a complete ring or circle, and at the center of this ring is a tubular member 6 joined to each of the wedge blocks 4 by means of tightening ele-

ment or rod 7, the purpose of which is to draw the blocks towards the center, and make the opposite inclined faces of the blocks 4 exert pressure upon the ends of the sections. In order to enable these rods 7 to 55 serve both for tightening purposes, and as electrical conductors, each rod may consist of a steel core 8, as shown in Figure 5, with a sleeve or coating 9 of copper of the like,

which will offer comparatively little resistance to the electrical current. The rods 7 may be affixed to the central member 6 in any suitable manner and the outer ends of the rods will be provided with threads 10

to receive nuts 11. When these nuts are 65 turned up they bear against the outer faces of the wedge blocks and force them in towards the member 6. Of course, these nuts

11 may be used with washers to afford a more advantageous engagement or bearing 70 of the nuts upon the wedge blocks, if desired. As shown in Figure 1, the sections 1 and the blocks 4 making up the complete

ring illustrated in Figure 1 are so assembled, 75 that each pair of sections is placed end to end with the adjacent sections, except for the interposition of the blocks 4 between the various pairs of sections 1. The sections of each pair have their ends justaposed, but

are so connected as to be in parallel with 80 each other, and thus all of the sections will be in multiple and joined on the one hand to a circular lead 12, secured to one of the

supply conductors 13 of the electric circuit in which the condenser is placed. In 85 between the sections of each pair are inserted

separator plates 14, which are also of some electrically conductive material and united 90 by short leads to the lead or bus bar 12, so that all of the sections may have one terminal joined to one extremity of the circuit through the bus bar 12 and conductor 13.

The other extremities of the sections abutting against the opposite faces of the wedge 95 blocks 4, may be connected to the other extremity of the electric circuit through the rods 7 and the tubular member 6; this tubular member being of some electrically conductive substance such as metal, and the

wedge blocks also being of some electrically 100

conductive material to enable the circuit through the various sections to be completed. Each section may consist of as many sheets of mica 2 and sheets of metallic foil 3 as is desired. The sheets of foil 3 of each section will be in series with one another and only the separator plates 14 between sections will be in electrical connection with the bus bar 12 and the adjacent wedge blocks 4. Each of these blocks as shown in Figure 4, may be made of a core of wood 15, in a coating or shell 16 of copper, the copper covering all the outer faces of the blocks. This kind of wedge block enables the assembled condenser to be much lighter, because the wood is of comparatively little weight. It also enables the various sections 1 to be easily put into electrical connection with the rods 7, and with the nuts 11 to tighten these wedge blocks, and on account of the high compressive strength of wood, the blocks can exert all the pressure desired on the ends of the sections 1. Besides serving as a terminal and as a stay for the rods 7, the tubular member 6 can also be made to act as a bearing so that the condenser can be mounted upon a suitable support.

A condenser of this type, assembled as described, made up of sections, the electrically conductive sheets of which are in series, while the sections themselves are in parallel, contains relatively small internal resistance and entails comparatively small losses in practice. By means of the nuts 11 and the rods 7, the wedge blocks 4 can be forced in towards the center of the ring of condensers far enough to exert as much pressure as is needed against the ends of the different sections; and act to force the sheets of mica and tinfoil tightly together and maintain them in firm engagement over their entire area. Thus the formation of cracks is prevented. The capacity of the condenser can be maintained at the desired value and high efficiency of operation easily secured. Further, with the wedge blocks made up chiefly of wood, but having an electrically conductive coating thereon, the losses of the condenser in operation are made considerably less than what they would be if solid metal blocks were employed. In Figure 6, I show a condenser comprising a central contact head 17, in a casing 18, and between this head and the inside wall of the casing 18, which may be round, are placed a number of sections 1, in radial positions, held between the head 17 at one end, and between metallic clamping blocks 19 at their opposite ends. The sides of the casing may carry a number of screws 20 engaging threaded holes in the sides of the casing and in line with the sections 1, so that when the screws are turned up, they force the sections tightly against the head and act in the same manner

as the wedge blocks 4 above described. From the top of the head 17 projects a central terminal rod 21, which may be reduced and threaded at its upper end to receive binding nuts 22 and enable the conductor of an electric circuit to be attached to this rod. 70

The top of the casing 18, which is closed, may have a central opening through which the rod 21 passes and surrounding this rod and secured at its lower end to the edge of this opening, may be a tubular member 23. This tubular member may carry a binding post 24 thereon to secure the other terminal of the electric circuit in which the condenser is to be placed, thereto, the casing 18 and the member 23 being of metal or the like, as will be understood. I may close the bottom of this condenser by a cover 25. Obviously, as many sections 1 may be mounted in the casing 18 in radial positions around the head 17 as may be necessary, and the head 17 may have a corresponding number of flat faces 26, so that the sections 1 may be clamped tightly over their entire cross-sectional area between the head 17 and the blocks 19. The central rod 21 acts as an inside conductor and the tubular member 23 as an outside conductor, and this arrangement of conductors for a condenser operating with short wave lengths confines the magnetic field, due to the current, and the electrostatic field, due to the charge in the condenser, so within the space between them, that the losses of the condenser in operation are materially reduced. 85 90 95

The inside of the casing 18 may be filled with some kind of insulating compound such as oil or wax impregnating the sections 1, or the casing may contain merely air between the interior surfaces thereof and the sections 1, and rod 21. Likewise, I may impregnate the sections 1 of the condenser shown in Figure 1, with wax or the like to insulate these sections more effectively. 100 105

In Figure 1, it will be observed that the sections of each pair have a common axis, but owing to the inclined opposite faces of the blocks 4, the various pairs of sections have their axes out of alignment, and thus the successive pairs of sections with the blocks 4 between them make up the complete circle or closed ring, and thereby the sections are very advantageously held together. 110 115

Obviously, a condenser constructed as shown in Figure 1 can be enclosed in the casing 18 with the tubular member 23 shown in Figure 6. When the condenser illustrated in Figure 1 is so enclosed, the tubular member 6 will be in the same position as the head 17 or member 17, and the separator plates will all be joined to the casing itself which will serve the same purpose as the bus bar 12, and one terminal of the circuit in which the condenser is to be used will be joined to the 120 125 130

binding post 24. The other terminal of the circuit will be attached to the tubular member 6 and will be led in through the tubular part 23, the same as the rod 21. For this purpose, the tubular member 6 may be extended out through the member 23 or a rod may be inserted through the member 23 and introduced into one end of the member 6 and electrically connected to the member 6. The 10 end of such a rod may be just large enough to fill the end of the member 6, so that the body of the rod extending up through the part or member 23 will be in central position.

15 Having described my invention, what I believe to be new and desire to secure and protect by Letters Patent of the United States is:—

1. An electrical condenser comprising sections arranged in pairs, the sections of each pair being in multiple and a wedge block between each pair of sections to enable pressure to be exerted thereon.

2. An electrical condenser comprising sections arranged in pairs, the sections being placed end to end, but with the axes of each pair out of alinement, and a wedge block between the pairs to enable pressure to be exerted thereon.

3. An electrical condenser comprising sections arranged in pairs, the sections of each pair being in multiple, and a wedge block between each pair of sections to enable pressure to be exerted thereon, in combination with a tightening element to act upon the wedge block to secure the desired pressure.

4. An electrical condenser comprising sections arranged in pairs, the sections being placed end to end, but with the axes of each pair out of alinement, and a wedge block between the pairs to enable pressure to be exerted thereon, in combination with a tightening element to act upon the wedge block to secure the necessary pressure to be obtained.

45 5. An electrical condenser comprising a plurality of sections arranged end to end to form a closed ring, wedge blocks in the ring, tightening elements engaging the wedge blocks and extending towards the center of the ring; and a member to which the wedge blocks are secured at the center of the ring.

60 6. An electrical condenser comprising a plurality of sections arranged to form a closed ring, wedge blocks to exert pressure on the ends of said sections, tightening elements to draw the blocks towards the center of the ring, a member at the center of the ring to which the said elements are secured, and a conductor joined to one terminal of each section, the other terminal of each section of the condenser being electrical connection with one of said wedge blocks, and 65 one of said elements.

7. An electrical condenser comprising a plurality of sections arranged in pairs, wedge blocks between each pair of sections, said blocks being of conductive material and being connected to one terminal of an electric circuit, and a terminal between the sections of each pair, said terminals being connected together to join the opposite ends of the sections to the other terminal of an electric circuit.

75 8. An electrical condenser comprising a plurality of sections arranged in the form of a closed ring, the sections being in pairs with wedge blocks between the adjacent pairs, tightening rods to draw the wedge blocks towards the center of the ring, a tubular member at the center of the ring to which the rods are affixed, plates between the sections of each pair, and a bus bar joined to said plates to enable the sections to be joined at one end to one terminal of an electric circuit, and at the other end through said blocks, said rods and said member to the other terminal of the electric circuit.

80 9. An electrical condenser comprising a wedge block and a tightening rod, said rod consisting of a strong core with a coating of relatively high electrical conductivity.

90 10. An electrical condenser comprising a wedge block consisting of a core of non-conductive material having a coating of electrically conductive material upon its outer faces.

95 In testimony whereof I affix my signature.
